UNITED STATES PATENT OFFICE.

DANIEL SULLIVAN, OF NEW YORK, N. Y., ASSIGNOR OF ONE-HALF TO
WILLIAM SLACK, OF SAME PLACE.

PULLEY-CRANE FOR CLOTHES-LINES.

SPECIFICATION forming part of Letters Patent No. 268,958, dated December 12, 1882.

Application filed June 19, 1882. (No model.)

To all whom it may concern:

Be it known that I, DANIEL SULLIVAN, of the city, county, and State of New York, have invented certain new and useful Improvements in Pulley-Cranes for Clothes-Lines; and I do hereby declare that the following is a full, clear, and exact description thereof, reference being had to the accompanying drawings, and to the letters of reference marked thereon, 10 making a part of this specification.

This invention, which relates to that class of clothes lines and fastenings used in the windows of dwellings, consists in the combination, with the crane-frame having a vertical 15 bar formed with a shoulder serving as a bearing, of a hook provided with a brace-arm and journal-eyes arranged upon the vertical bar about midway between the pivots of the crane, as will be hereinafter more fully set forth.

20 In the accompanying drawings, Figure 1 is a view in perspective of my improved pulley-crane applied to a window, illustrating it as swung into the room to facilitate the placing of the clothes upon the line. Fig. 2 is an elevation, on an enlarged scale, of the crane when 25 swung out from the window, with the rope thrown over the slack-hook to maintain its tension.

30 A is the beam, B the post or upright bar, and C the brace-bar, of the crane. The post B is supported and pivoted, top and bottom, in eyes formed in lugs D D projecting from a plate, E, adapted to be secured to the outside of the window-frame.

35 If preferred, the upright post may be fitted, top and bottom, with hooks adapted to hook into the eyes D D, or into eyebolts to be screwed into the window-casing, dispensing with the plate E.

40 The crane swinging upon the hooks will admit of ready detachment therefrom when required.

These devices are all well known, and my improvement may be adapted to and employed 45 with any form of swinging arm properly supported and pivoted to the outer frame of the window to swing in and out through the window-casing, so that the outer free end of the arm may project into the room.

50 The letter F represents the upward-bent

hook, journaled to the post B of the crane. The hook F is stayed and braced to resist the heavy strain thereon by means of an arm, f, which is carried down parallel with the post and journaled thereto, as shown in the drawings, the hook thus braced being upheld at the proper point about midway between the pivots of the crane by means of an annular offset or shoulder, h, formed upon the post.

55 A pulley, G, is secured to the outer end of the beam A, and the clothes-line K is led thence in an endless chain around a second pulley fixed at a suitable point outside of the window, the line being long enough to permit the beam to swing freely into the window. A 60 long hook, L, is loosely suspended from the beam to facilitate swinging it in and as a device for securing the same when it is swung into the room, the hook being adapted to engage a suitable eye fixed on the inside of the 65 window-casing for the purpose, as shown in Fig. 1.

In operation, the window being opened, the 70 beam A is swung around into the room, bringing the pulley G and the line K with it. The 75 line may now be lifted off from the hook F and left hanging slack and free, as shown in Fig. 1, to run easily over the pulleys, and the clothes can be hung thereon in the room without reaching 80 out of the window and without exposure or inconvenience to the person using the apparatus. After the clothes have been placed upon the line and run out, as required, the line is lifted up over the hook F, (see dotted line, Fig. 1, and see Fig. 2,) and the beam may then 85 be swung out to allow the window to be closed without any slackening of the tension of the line, the swinging out of the beam serving, in fact, to fix and lock the line by doubling it around the hook, as shown in Fig. 2.

90 By this described organization and arrangement the hook is placed in such a position that it is easily reached, whereas when placed at the top it becomes difficult for a weak woman to lift the line filled with clothes on account of 95 the necessary height, and the advantage of mounting the hook upon the vertical rod is apparent to those having occasion to use these lines.

I claim as my invention—

In a clothes-line hanger, the combination, with the crane-frame having the vertical bar B, formed with the shoulder *h* serving as a bearing, of the hook F, provided with the brace-arm *f*, and journal eyes arranged upon the vertical bar B about midway between the pivots of the crane, substantially as described.

In testimony whereof I have signed my name to this specification in the presence of two subscribing witnesses.

DANIEL SULLIVAN.
